[57] CLAIM

The ornamental design for a grip for a tennis racquet handle, as shown and described.

DESCRIPTION

FIG. 1 is a front elevational view of a grip for a tennis racket handle showing my new design, the undisclosed opposite side being identical; and,

FIG. 2 is a side view thereof, the undisclosed opposite side being identical.

The broken line showing of the neck and fragmented head portion of the tennis racket is for illustrative purposes only and forms no part of the claimed design.
